UNITED STATES PATENT OFFICE.

JAMES J. McDONALD, OF CLEVELAND, OHIO.

HEATING SYSTEM.

1,116,311.

Specification of Letters Patent.

Patented Nov. 3, 1914.

Application filed May 7, 1910. Serial No. 559,885.

To all whom it may concern:

Be it known that I, JAMES J. McDONALD, a citizen of the United States, residing at Cleveland, in the county of Cuyahoga and State of Ohio, have invented a certain new and useful Improvement in Heating Systems, of which the following is a full, clear, and exact description, reference being had to the accompanying drawings.

10 This invention relates generally to an apparatus for automatically regulating the flow of one fluid by variations in the condition or pressure of another fluid. While my apparatus is particularly useful in connection with heating systems in which steam is circulated at a pressure below or nearly equal to that of the atmosphere, it will be understood that certain features thereof are of general application, being 20 adapted for use wherever it is desirable to control or regulate the flow and pressure of fluids. Generally speaking, the invention may be defined as consisting of the combinations of elements embodied in the claims 25 hereto annexed and illustrated in the drawings forming part hereof, wherein—

Figure 1 represents an elevation of a system embodying my invention; Fig. 2 represents a vertical sectional detail of a trap employed with said system; Fig. 3 is a sectional detail corresponding to the line 3—3 of Fig. 2; Fig. 4 is a sectional detail of the automatic valve by which the operation of the pump is controlled; and Fig. 5 is a sectional detail of the liquid chamber interposed between the two portions of the pump shown in Fig. 1.

Describing the parts by reference characters, 1 denotes a pipe which may conduct 40 air from a radiator or series of radiators. This pipe is provided with a valve 2 and a separator 3 having a connection 4 by means of which sediment may be discharged, through a valve 5 and check valve 6, into 45 a pipe 7, the lower end of which discharges into a sewer or other place adapted for the reception of waste water. From the upper portion of the separator 3 there extends a pipe 8, which is connected with the operating cylinder 9 of a pump, the power cylinder of which is shown at 10. The pipe 8 communicates with opposite ends of the cylinder

9, through connections 11 and 12, the former connection being located at the lower end of the cylinder and the latter at the upper end and being connected to pipe 8 by a pipe section 13. The cylinder 9 is connected at its opposite ends with the pipe 7 by means of outlet connections 14 and 15 and a pipe section 16, the outlet connection 15 being located at the lower end of the cylinder and being connected with 14 by means of a pipe section 17. The pump is shown herein conventionally and it will be understood that suitable check valves will be provided 55 with the connections 11, 12, 14 and 15 to cause the piston 18 to alternately exhaust from the connections 11 and 12 and discharge alternately through connections 14 and 15. The piston 18 is connected by a piston rod 19 with the power piston 20 in the lower cylinder 10.

The pipe 8 is shown as formed into a bend or coil within the chamber 21. This chamber is intended to receive water from a supply 22 and discharge the same, through an automatically-operating valve 23, into a pipe 24 which communicates with the cylinder 10 for the purpose of operating the piston 20 therein. The exhaust from the cylinder 10 is discharged through a pipe connection 25 into the pipe 7.

The automatic valve 23 is preferably of the general type shown in my application 334,882, filed September 17, 1906, and comprising a casing 26 having an inlet connection 26^a for the pipe 22^a which communicates with the chamber 21. The casing 26 is provided with a differential valve 27, and this valve comprises a double piston the upper piston 28 of which is connected by an integral sleeve 29 with the lower combined piston and valve disk 30. The lower surface of the disk 30 is recessed for the reception of the packing or washer 31. The valve 32 fits a port in the lower portion of the valve casing 26 while the stem 32^a extends through the sleeve 29 and is provided at its upper end with the adjusting sleeve 33 resting upon the upper surface of the piston 28. The packing 31 rests upon an annular seat 34 surrounding the valve 32. A spring 35 is inserted in the upper portion of the casing and has its lower end engaging the

piston 28 and its upper end engaging the lower end of a plug 36.

The plug 36 serves as a connector between the casing 26 and the diaphragm chamber 37. This plug is provided with an upper bore for the reception of the stem of a valve 38 and with a lower smaller bore 39 communicating with the upper portion of the casing 26 and with a chamber 40 in said plug. 10 The plug is provided with a bore 41 extending laterally through a wall thereof and communicating with the chamber 40. The upper end of the valve stem bears against the lower surface of a diaphragm 42 in the chamber 37 and the said stem is provided with a stop 43 between which and the upper end of the plug 36 is inserted a spiral spring 44.

The diaphragm 42 is retained in place by 20 means of a chambered member 45 having its lower end threaded into the upper end of chamber 37 and being provided at its upper end with an internal thread for the reception of a nipple 46, the upper end of 25 which is in turn threaded into the lower portion of a diaphragm chamber 47. 48 denotes a diaphragm extending across the upper end of the chamber 47 and 49 a metallic inverted cup which is secured to the 30 lower surface of said diaphragm and is adapted to seat on the subjacent portion of the chamber 47 when the pressure of the atmosphere on the top of the diaphragm 48 is considerably in excess of the pressure 35 within said chamber as affected by the action of a spring, which will be described later.

The member 45, nipple 46 and chamber 47 provide a conduit connecting the opposed sides or faces of the diaphragms 42 and 48. 40 The member 45 is provided with a bore or connection for the reception of a pipe 50 which connects the same with the portion of the pipe 8 extending downwardly from chamber 21.

45 51 denotes a rod, the upper end of which is reduced and extended through the cup 49 and diaphragm 48, the lower end of said rod bearing against the upper surface of the diaphragm 42, opposite the upper end 50 of the stem of the valve 38. The upper end of the rod 51 is conveniently threaded into and continued by a rod 52 which extends upwardly through the cross bar and apex of an A-shaped frame 53, which frame is 55 carried by the ring 54 which clamps the outer edge of the diaphragm 48 to the upper edge of the cup 47. The upper end of the rod 52 is threaded and is provided with a wing nut 55, between which and the apex 60 of the frame 53 there is interposed a spring 56. By adjusting the nut 55, the tension of the spring 56 may be varied to secure the proper relation between the operating pressure within the chamber 47 and the atmos-

pheric pressure acting on top of the diaphragm 48.

57 denotes a chamber, to the lower end of which a pipe 58 is connected, the other end of said pipe being connected with the bore 41. The upper end of the chamber 57 is 70 connected by means of a pipe 59 with the pipe 7. The arrangement of the pipes 58 and 59 provides a seal including the chamber whereby said chamber is kept substantially filled with liquid at all times under a 75 material head. The piston rod 19 extends through the chamber 57 and is liquid-packed thereby. The chamber is made of two sections, each having vertically-extending flanges 57^a by which the sections may be 80 bolted together. Each chamber section is provided at the top and bottom thereof with a semi-circular recess, each recess in one section being adapted to form, with a complementary recess in the other section, a circular opening. The piston rod 19 extends through the circular opening thus provided in the chamber 57 and is packed by the construction shown in Fig. 5. Sleeves 60 and 60^a extend through the upper and the lower 90 apertures, respectively, of said casing. The upper end of the sleeve 60 and the lower end of the sleeve 60^a are provided each with a packing nut. These nuts are shown at 61 and 61^a and are threaded on to the exterior 95 of the packing chambers 62, 62^a projecting from the cylinders 9 and 10, respectively. Packing 63, 63^a is inserted into said chambers and is adapted to be compressed around the piston rod 19 by means of follower rings 100 64, 64^a mounted in said packing nuts. The ends of the sleeves 60 and 60^a project into the chamber 57, the lower end of the former sleeve extending below the outlet pipe 59, whereby the lower end of the sleeve is always 105 water-sealed.

In Figs. 2 and 3 I have shown the construction of separator employed in the air line. The separator comprises a casing 3, which is provided with a laterally projecting boss 65 for the lower end of the pipe 1 and with a similar boss 66 opposite the boss 65 and slightly below the same; the latter boss receiving the pipe 8. The bottom of the casing 3 is funnel-shaped and is provided with a boss 67 having an internal thread for the reception of the upper end of the pipe 4. As will be observed by special reference to Fig. 2, the inclined bottom overhangs the threaded aperture in the boss 67 110 to such an extent as to form a ledge 68 against which the upper end of the pipe 4 may abut, which ledge overhangs the upper end of said pipe and prevents the accumulation of sediment thereon.

The casing 3 is provided with a baffle 69 projecting downwardly from the top and preferably cast therewith. This baffle pro-

jects a considerable distance below the point at which the pipe 1 discharges into the casing and has its lower end beveled, as shown at 70, with the extreme lower end of 5 the baffle directly above the center of the outlet in the bottom of the casing. 71 denotes an annular flange cast with the casing 3 and baffle 69. This flange is located immediately below the boss or connection 10 66 and is provided with an annular seat 72 located below its upper surface and preferably separated therefrom by an abrupt shoulder 73. The upper end of the casing 3 is provided with a threaded aperture directly above the seat 72. This aperture is 15 provided with a plug 74, which plug is provided with an internal seat 75 corresponding to the seat 72, and said plug is concaved within said seat, as shown at 76. The casing 20 may be provided with another boss 77 located above the boss 66 and shown in dotted lines in Fig. 2, which boss may afford a connection to other apparatus or systems. The casing 3 may be provided also 25 with a nipple 78 establishing communication with a pressure gage 79.

The seats 72 and 75 are for the reception of a cylindrical screen or strainer 80, preferably of wire gauze. The concavity in the 30 lower end of the plug 76 serves to center the screen 80 in assembling the parts and also to throw down any sediment, which may pass with the fluid into the strainer, into the inclined lower end of the casing 3. The arrangement of the baffle 69 serves to separate 35 much of the sediment from the fluid passing through the casing, by throwing the same downwardly into the lower inclined portion of the casing. This operating is rendered 40 more certain by the construction and location of the parts including the inlet connection 65, the outlet connections 66 and 67 and the baffle 69. The beveling of the lower end 45 of the baffle prevents any accumulation of sediment thereon.

With the parts constructed as described, the operation will be as follows: When the pressure in the pipe 8, aided by the spring 50, and acting through the connection 50, is 50 sufficient to force the diaphragm 48 upwardly against the pressure of the atmosphere, the lower end of the rod 51 is moved away from the diaphragm 42, and the spring 44 will unseat the valve 38, thereby 55 venting the chamber in the upper end of casing 26 through the bore 39 and the pipe 58. This will permit water from the pipe 22, casing 21 and pipe 22 to lift the piston 28 and valve 32, and water will then flow to the 60 power cylinder 10 to operate the pump. This will cause the piston 18 to exhaust the air from the pipe 8 and discharge it into the pipe 7. The water flowing from the automatic valve through the pipe 58 forms an

efficient liquid-packing for the piston rod 65 to prevent the leakage of air, such leakage being resisted by the head of the water. The chamber 57 not only provides a water packing for the piston rod but also protects the rod from dust, ashes, etc., that would otherwise adhere thereto and eventually cut the packings and piston rod. Furthermore, the stuffing boxes through which the piston rod passes may be adjusted without disturbing the chamber 57. Meanwhile, the temperature of the air flowing through the pipe 8 has been lowered by means of the water in the chamber 21 coming into contact with the coil in the pipe 8, so that this air may enter 70 into and be discharged from the cylinder 9 75 without injury to the leather, rubber or other packings that may be used in connection with such cylinder. The flow of water through the chamber 21 occurs simultaneously with the flow of relatively heated fluid 80 through the coil of the conduit 8, owing to the automatic operation of the pump by 85 pressure conditions in said conduit.

Having thus described my invention, what I claim is:

1. In a heating system, the combination of an air-exhaust conduit, means for automatically exhausting air through said conduit, said means comprising a pump connected to said conduit, a second conduit for 90 supplying pressure fluid to said pump to operate the same, means governed by the pressure in the former conduit for controlling the supply of pressure fluid to the pump, and means whereby the pressure fluid 95 may cool the air in the former conduit prior to its admission to the pump.

2. In a heating system, the combination of a pump having a power or motor cylinder and an operating cylinder, a conduit for 100 supplying liquid to the former cylinder to operate the pump, an automatic device for controlling the flow of liquid through said conduit, an air exhaust conduit extending to the second cylinder of the pump, a connection 105 between said conduit and the automatic device in the first-mentioned conduit whereby said device may be operated by pressure conditions in the second conduit, and means for cooling the air in the exhaust conduit by 110 the liquid employed to operate the pump.

3. In a heating system, the combination of an air-exhaust conduit, a pump connected to said conduit, a second conduit for supplying water to said pump to operate the same, means whereby the water which operates the pump may pass in cooling relation to the air in the former conduit, and means for simultaneously instituting the flow of air and water through their respective conduits.

4. In a heating system, the combination of a pump having a power cylinder and an operating or pumping cylinder, a pressure

- fluid conduit communicating with the first-mentioned cylinder, a fluid conduit connected with the other cylinder, a chamber through which one of said fluids flows and inclosing a part of the conduit for the other fluid, and means controlled by pressure conditions in one of said conduits for simultaneously instituting the flow of fluids through both of said conduits.
- 10 5. In a heating system, the combination of a pump, a liquid conduit communicating therewith, said conduit including a chamber, an air-exhaust conduit connected with the operating part of said pump and extending through said chamber, and means whereby the supply of liquid through the chamber may be controlled by pressure conditions in the air-exhaust conduit.
- 15 6. In a heating system, the combination of a pump having a power cylinder and an operating cylinder, a piston in each of said cylinders, a rod connecting said pistons, a chamber interposed between said cylinders, sleeves projecting from said cylinders into said chamber and surrounding said piston rod, an air-exhaust conduit connecting the heating system with the operating cylinder, a pressure-fluid supply connected with the power cylinder, means whereby said chamber may be filled with liquid under a material head and means for cooling the air admitted to the operating cylinder.
- 20 7. In a heating system, the combination of a pump having a power cylinder and an operating cylinder, sleeves projecting from adjacent ends of said cylinders, a piston in each cylinder, a piston rod connecting said pistons and extending through said sleeves, a chamber inclosing the outer ends of said sleeves, means for maintaining in said chamber a supply of liquid under pressure, an air-exhaust pipe connecting the heating system with the operating cylinder, a pipe for supplying fluid under pressure to the power cylinder and means for cooling the air admitted to the operating cylinder.
- 25 8. In a heating system, the combination of a pump comprising a power cylinder and an operating cylinder, sleeves projecting from adjacent ends of the power and operating cylinders, a chamber inclosing the outer ends of said sleeves, a pipe for supplying liquid under pressure to the power cylinder, a pipe into which said power cylinder discharges, a liquid-supply pipe communicating with the former pipe and with said chamber, an outlet pipe extending from the upper portion of said chamber and connecting with the second pipe, an air-exhaust pipe, a connection between said pipe and the operating cylinder and means for cooling the air admitted to the operating cylinder.
- 30 9. In a heating system, the combination of a pump having a power cylinder and an operating cylinder, a sleeve projecting from each of said cylinders toward the other, a chamber inclosing the outer ends of said sleeves, a piston in each of said cylinders, a piston rod connecting said pistons and extending through said sleeves and said chamber, an air-exhaust pipe connecting the heating system with the operating cylinder, a pressure-fluid conduit connected with the power cylinder, a liquid-supply pipe connected with the chamber, said chamber being provided with an outlet pipe, means coacting with said sleeves to pack said rod outside said chamber and means for cooling the air admitted to the operating cylinder.
- 35 10. In a heating system, the combination of a pump having a suction cylinder, a piston therein, a piston rod extending through the end of said cylinder, a sleeve surrounding said rod outside said cylinder, a chamber inclosing the outer end of said sleeve, means for operating said piston, a liquid-supply pipe communicating with said chamber and substantially filling the same with liquid under pressure, an air-exhaust pipe communicating with the heating system, a connection between said pipe and the cylinder and means for cooling the air supplied through said pipe to the cylinder.
- 40 11. In a heating system, the combination of a pump having a power cylinder and an operating cylinder, a piston in each of said cylinders, a rod connecting said pistons, a chamber interposed between said cylinders and through which said rod extends, an air exhaust conduit connecting the heating system with the operating cylinder, a pressure fluid supply connected with the power cylinder, means whereby the chamber may be kept substantially filled with liquid and means for cooling the air admitted to the operating cylinder.
- 45 12. In a heating system, the combination of a pump having a power cylinder and an operating cylinder, a piston in each of said cylinders, a piston rod connecting said pistons, a chamber interposed between said cylinders and through which said rod extends, an air exhaust conduit connecting the heating system with the operating cylinder, a pressure fluid supply connected with the power cylinder, means whereby the chamber may be filled with liquid under a material head and means for cooling the air admitted to the operating cylinder.
- 50 13. In a system of the character described, the combination with an exhaust pipe of an exhaust pump communicating therewith, a motor operatively connected with said pump, means for supplying motive fluid to said pump, said means being arranged in heat conductive relation to said exhaust pipe whereby said motive fluid may be used to cool the fluid in said exhaust pipe.
- 55 14. In a system of the character described,

the combination with an exhaust pipe of an exhaust pump communicating therewith, a motor operatively connected with said pump, means for supplying motive fluid to said pump, said means being arranged in heat conductive relation to said exhaust pipe whereby said motive fluid may be used to cool the fluid in said exhaust pipe, and automatic means controlled by the pressure

within said exhaust pipe for governing the supply of motive fluid to said pump.

In testimony whereof, I hereunto affix my signature in the presence of two witnesses.
